CONTROL RECORDING INSTRUMENT

Paul Arthur Aldinger, Warminster, Pa., assignor to Honeywell Inc., Minneapolis, Minn., a corporation of Delaware

Filed May 3, 1966, Ser. No. 2,143

Term of patent 14 years

(Cl. D52—7)

FIG. 1

FIG. 2

FIGURE 1 is a front and right side perspective view of a control recording instrument showing my new design;

FIGURE 2 is a sectional view looking in the direction of the arrows on line 2—2 of FIGURE 1;

The undisclosed side is substantially the same as the side shown, and the bottom is substantially the same as the top, the rear of the housing being plain.

The serrations in the circular knobs in FIG. 2 are understood to be continued throughout the broken line are for convenience of illustration.

I claim:

The ornamental design for a control recording instrument, substantially as shown and described.
